UNITED STATES PATENT OFFICE

2,482,264

TELEGRAPH SYSTEM

Maurus T. Goetz, Chicago, Ill., assignor to Teletype Corporation, Chicago, Ill., a corporation of Delaware

Application July 14, 1945, Serial No. 605,082

12 Claims. (Cl. 178—3)

1

The present invention pertains to telegraph systems, and more particularly to systems incorporating both multiplex and start-stop transmission and apparatus.

On multiplex channels the use of a "blank" combination indicates an idle condition, and therefore means are usually provided at the receiving end to suppress "blanks." In the event that start-stop channels and apparatus are connected to such multiplex channels and messages are transmitted containing needed "blank" combinations, it becomes necessary to provide means to distinguish the "blank" combination from an idle channel condition.

Accordingly, an object of the present invention is to provide means for determining the difference between a "blank" combination and an idle channel condition.

A further object of the invention is to convert a "blank" combination to a different character combination and a "letters" combination for multiplex transmission and to reconvert the combinations to a "blank" combination.

Inasmuch as there are a limited number of code combinations available in the five unit Baudot code, in the event that a "blank" combination is converted to a different character combination the latter will thus be useless for intelligence communication, which under certain conditions is undesirable.

Accordingly, a further object of the invention is to provide means whereby no code combinations will be sacrificed, to achieve the objects set forth previously.

Still another object of the invention is to provide means to convert the character combination used to designate the "blank" combination to a double character combination, and thereafter to reconvert to a single combination.

Another object of the invention is to convert predetermined code combinations only to different code combinations, and to reconvert them to the original code combinations.

A still further object of the invention is to provide means to distinguish between various code signals.

An embodiment of the invention, utilized with perforator transmitters, comprises, at the start-stop to multiplex changeover, a plurality of reading contacts and relays operating to convert a "blank" combination to a different character combination and a "letters" combination and to convert the different character combination to a double character combination. Likewise, means are provided including reading contacts and re-

2

lays to reconvert to the original characters at the multiplex to start-stop routing point.

The features and advantages of the invention will become apparent from the following detailed description of a specific embodiment thereof, when read in conjunction with the accompanying drawings, in which

Fig. 1 shows a block diagram of the contemplated system;

10 Fig. 2 shows the means to convert the code combinations at the point of start-stop to multiplex change;

15 Fig. 3 shows the means to reconvert to the original code combinations at the routing point from multiplex to start-stop transmission, and

Fig. 4 illustrates a partial view of apparatus with which the present invention may be readily utilized.

20 The specific embodiment of the invention has been shown in conjunction with a start-stop perforator transmitter of the type disclosed in U. S. Patent No. 2,348,214, issued to E. A. Gubisch on May 9, 1944. Fig. 4 of the instant drawings is a portion of Fig. 2 of the Gubisch patent, with 25 the identifying numerals changed to apply to the following description. It is to be understood, however, that the invention is not limited to incorporation with such apparatus but may be utilized with signal transmitting and receiving 30 apparatus of any suitable type.

Referring particularly to Fig. 1, apparatus is disclosed for converting signals in the start-stop to multiplex routing. The apparatus at such station contemplates the use of a start-stop perforator transmitter 11 which is of the type disclosed in the above-identified patent. A relay bank 12 is provided in conjunction with the transmitter 11 and a multiplex distributor 13 is provided in conjunction with the relay bank 12.

35 The perforator transmitter 11 operates from a tape which is shown in Fig. 1 of the instant drawings and which is sensed by means of a plurality of feeler levers (not shown) in a manner well known in the art. As a result of the sensing 40 operation of such feeler levers, a plurality of slides 14 (Fig. 2) are ultimately set in accordance with the marking or spacing characteristic of the particular code combination. The slides 14 operate through a projection 16 forming part of 45 each of a plurality of contact operators 17 which are pivoted on a shaft 18, all as is clearly described in the above-identified patent, and as is shown in Fig. 4. It is not deemed necessary to 50 describe the operation of the elements of Fig. 4 as a complete description may be found in the 55

Gubisch patent. The contact operators 17 have an elongated section 19 which has a plurality of lugs 21 thereon, each of which engages an associated swinger to control the operation thereof in a manner which will be described hereinafter.

A shaft 22 is provided which controls the operation of the setting of the swingers described above and which also has cams 23 and 24 thereon for causing operations which also will be described hereinafter. The shaft 22 is under the control of a clutch magnet 26 to release said shaft for operation as will be described. A second shaft 27 is provided which has a plurality of cams 28 thereon which control the transmission of start-stop code signals over a start-stop circuit 29. Such start-stop transmission may be utilized to control a monitor printer at the local station, which is not shown in the present invention, or may be utilized for start-stop transmission to any other locality. The shaft 27 is under the control of a clutch magnet 31, as will hereinafter be described.

If it is assumed that the transmitter 11 is operating with the slides 14 being positioned in accordance with the permutations in the tape, the contact operators 17 will likewise be positioned in accordance with the operation of the slides through the projections 16 and because of the lug 21 extending from the elongated portion 19 will cause the operation of a first set of electrical contacts 32 in accordance with the setting of the slides 14.

By reference to the cams 28 on the shaft 27, it may be seen that each of these controls an associated cam follower 33 which is pivoted at 34 and has a downwardly extending contact operating arm 36. The cam followers 33 are each normally biased in a clockwise direction into engagement with the periphery of their associated cam by means of an individual spring 37. Upon rotation of the shaft 27, because of the staggered recesses in the cam with respect to each of the follower levers 33, the follower levers will be operated sequentially in a clockwise direction to cause the downward extension 36 thereof to close an associated contact pair 38.

By reference to the drawing it may be seen that the lowermost cam follower 33 is normally biased in a clockwise direction to close its associated contact pair 38 because of the fact that when the shaft 27 is at rest, the recess of the cam 28 associated with the lowermost cam follower 33 is presented to the cam follower thereby allowing the contact pair 38 to be closed. Under this condition an electrical circuit is established from positive grounded battery 39, through the normally closed contact pair 38, over a conductor 41, and over the start-stop circuit 29. This condition is the normal idle condition on the start-stop circuit with marking battery on the line.

If it is further assumed that the shaft 22 is operating, at a particular time in its cycle of rotation the cam 23 thereon will allow an associated follower lever 42 to be biased in a clockwise direction under the urging of its spring 43 to close an associated contact pair 44. At this time an electrical circuit will be established from positive grounded battery 46, through the closed contact pair 44, over a conductor 47, and through the winding of a clutch release magnet 31 to ground. Such operation will cause the shaft 27 to be released for rotation thereby opening the lowermost contact pair 38 through the resulting counterclockwise actuation of the follower lever

33 associated therewith with the resultant removal of a marking condition from the circuit 29. After this contact pair is opened a zero or start condition will exist for a predetermined time. Immediately thereafter the remaining five contact pairs 38 will be closed sequentially in a manner which has previously been described. Upon the closure of the contact pairs 38 code impulses will be transmitted over the conductor in accordance with the sensing of the perforations in the tape in a manner which will now be described.

If it is assumed that the particular code combination that has been sensed in the tape comprises a marking and spacing condition, respectively, for the first two impulses, the uppermost contact pair 32 will be closed whereas the second contact pair 32 (immediately therebelow) will be open.

With respect to the top contact pair 32, at the time that the uppermost contact pair 38 is closed an electrical circuit will be established from grounded positive battery 48, over a common conductor 49, through the uppermost contact pair 32, over a conductor 51, through the closed uppermost contact pair 38, over a conductor 52, and over the common conductor 53 to the start-stop circuit 29. Thus, a marking impulse will be transmitted over the circuit under this condition.

Considering now the second contact pair 32 which we have assumed to be in an open condition due to the sensing of a spacing condition (no perforation) in the tape with respect to the second contact pair 38 at such time as that contact pair is closed no electrical circuit may be established from the battery 48, through a circuit similar to the one just described because of the fact that as mentioned the contact pair 32 associated therewith is open. Such being the case, a zero electrical or spacing condition will occur on the circuit 29 during this interval. Thereafter, the remaining three contact pairs 38 will be closed at successive intervals and will cause marking or spacing impulses to be transmitted over the circuit 29 in accordance with the settings of their associated contact pairs 32 under the control of the tape in a manner which has just been described.

After the shaft 27 has completed a cycle of operation it will come to a stop condition and will remain in such condition until such time as the clutch release magnet 31 is once again energized to release it for another cycle of operation. Such will occur after the shaft 22 once again assumes a position whereat the depression in the cam 23 is presented to the follower lever 42 thereby once again closing the contact pair 44 and establishing the circuit described previously.

The start-stop circuit 29 will be under the control of the apparatus described above to transmit code signals to its associated receiving equipment. Inasmuch as this does not form part of the present invention, however, further description thereof is not deemed necessary with the exception that the time of closure of the contact pair 44 with respect to the entire apparatus will be pointed out hereinafter.

The elongated section 19 of a contact operating lever 17 not only controls a contact pair 32 through its lug 21, but through a similar lug controls a movable swinger 54 which in a normal or unoperated position will be in engagement with a right-hand contact 56 and in an operated or selected condition will be in engagement with

a left-hand contact 57. The elongated portion 19 through another lug 21 also controls a movable swinger 58 which in its normal unoperated condition is in engagement with a right-hand contact 59 and in a selected condition is in engagement with a left-hand contact 61. Likewise, another lug 21 also controls a movable swinger 62 which is normally in engagement with right-hand contact 63 but when moved to a selected position engages a left-hand contact 64. While the above description has been given with respect to a particular elongated portion 19 of contact operating lever 17 and the swingers which it controls, it is to be understood that each of the five contact operating levers 17, each designating one of the impulses of the five unit code, will control in a similar manner similar swingers 54, 58, and 62.

If it is assumed that the transmitter 11 is in an unoperated condition with all of the slides 14 in an unselected position, which indicates that their associated feeler has not sensed a perforation in the tape or that no tape is present in the apparatus, the elongated section 19 will be in its extreme right-hand position thereby resulting in the swingers 54, 58, and 62 being in engagement with their right-hand contacts 56, 59, and 63, respectively. Under this condition an electrical circuit may be traced from positive spacing grounded battery 66, over common conductor 67, through the contacts 63, through the swingers 62, and over individual conductors 68 to the relay bank 12 for a purpose to be described hereinafter. It might be mentioned at this point that this condition of positive battery or "blank" on the line indicates an idle condition under multiplex transmission, such condition being spacing on the line.

As has been previously mentioned, the swingers 54 and 58 are also in their unselected or right-hand position in engagement with their associated contacts 56 and 59, respectively. It is sufficient to state at this time that no electrical circuit will be established due to such positioning of the swingers 54 and 58 because in an unoperated condition of the transmitter 11 and particularly the shaft 22, the cam 24 thereon will not permit its associated spring to bias its associated follower 69 in a clockwise direction to allow the closure of associated contact pair 70 thus precluding the establishment of an electrical circuit from the grounded battery 46, through the contact pair 70. The significance of this contact pair 70 and the operation as a result of its closure will be described fully hereinafter.

If reference is now made to the multiplex distributor 13 it may be seen that it comprises a ring 71 having a plurality of segments thereon, the first five of which are connected over conductors 72 to the relay bank 12. The segmented ring 71 is contemplated to include twenty segments, thereby providing for transmission over four channels, one of which is disclosed in the instant drawings. The segmented ring 71 is bridged by means of an associated brush in a manner well known in the art with a solid transmitting ring 73 to initiate multiplex code signals over a line conductor 74. The multiplex distributor 13 is further provided with a local solid ring 76 which is connected to positive grounded battery 77. Solid ring 76 is bridged by an associated brush with a local ring 78 which is provided with local segments thereon, one of which, 79, is shown. A segment 79 is associated with each of the multiplex channels.

If it is assumed that the present apparatus has

not been operating and that the distributor brush has traversed the segment 79 of the local ring 78, an electrical circuit will be established from grounded battery 77, through the solid ring 76, over the brush in a well known manner, through the segment 79, over a conductor 81, through an armature 82 to lower contact 83 with which it is normally in engagement, over a conductor 84, through an armature 86 to lower contact 87 with which it is normally in engagement, over a conductor 88 to junction point 89, over conductor 91, through the winding of clutch release magnet 26, through a manually operable switch 92 which will now be closed, over a conductor 93 and through a swinger 94, through contact 96 normally in engagement therewith, to ground. Upon the establishment of the circuit just traced, the clutch release magnet 26 will be energized, thereby resulting in the release of the shaft 22 for rotation.

The swinger 94, which has been described as normally being in engagement with contact 96, is under the control of a member 97 which, as is described in the above-identified patent and is also illustrated in Fig. 4, operates when the pivoted sensing device is in engagement with the punch block thereby indicating that the last code combination in the tape has been sensed and that no more tape is available for transmission. Under such condition the member 97 would cause swinger 94 to be biased in a counterclockwise direction removing it from engagement with contact 96 and thereby precluding the energization of the clutch release magnet 26, even though the distributor brush traverses the segment 79.

The switch 92 previously mentioned is provided so that if it is desired to preclude operation of the instant apparatus the switch will be opened thereby preventing the establishment of the circuit for magnet 26. Under this condition the clutch release magnet 26 will not be energized, assuming that the switch 92 has been placed in an open position, even though the brush traverses the segment 79.

During the first part of the cycle of rotation of the shaft 22 the feeler levers will be removed from the tape thereby allowing the tape to be stepped and thereafter will be once again placed in probing engagement with the tape to thereby set the slides 14 and the contact operators 17 in accordance with the impulse characteristics or conditions in the tape.

Just prior to the setting of the contacts in accordance with the code combinations in the tape, the cam 23 on the shaft 22 will operate to close the contact pair 44 and thereby cause the energization of the clutch release magnet 31, as has been described. Such results in marking battery 39 being removed from the line conductor 29 and a zero condition or start pulse being transmitted on the line. During the transmission of the start pulse the contacts under the control of the contact operators 17 will be set and thereafter the contacts 38 will be closed sequentially to transmit marking or spacing impulses over the line conductor 29.

Inasmuch as swingers 62 will now be positioned in accordance with the code combinations in the tape they will not all remain in their right-hand position in engagement with associated contact 63 unless the particular combination sensed happens to be an all-spacing or "blank" combination. Assuming that such is not the case and that certain of the swingers 62 have been moved to their left-hand position in engagement with associated

75 left-hand position in engagement with associated

contact 64, an electrical circuit will be established from negative grounded marking battery 98, over common conductor 99, through contacts 64, through swingers 62 which have been moved to the left and over conductors 68 to the relay bank 12. Unless the particular code combination is an all marking or "letters" combination certain of the swingers 62 will remain in their unselected or right-hand position in engagement with associated contact 63. Under this condition the previously described electrical circuit from positive spacing battery 66 to conductors 68 will be established. Under the conditions described above, the code combinations sensed of marking and spacing impulses will be passed over the conductors 68 to the relay bank 12. The above operations will be repeated for each character to transmit message intelligence over the multiplex circuit through the relay bank 12 and over the segmented and solid rings 71 and 73, respectively, in a manner which will be described hereinafter. The transmitter 11 will be reset to a new code combination every time that the brush traverses the segment 19 of the local ring 73 to re-energize the selector magnet 26. It should be noted, as previously mentioned, that the instant apparatus utilizes one channel only of the multiplex circuit and, therefore, the tape will be stepped and the contacts set while the brush is traversing segments similar to the first five segments of segmented ring 71 associated with other multiplex channels. Thus, the instant apparatus will be in readiness to transmit a code signal at such time as the brush traverses the first five segments of the segmented ring 71.

If it is assumed that a "blank" code combination is sensed in the tape, the selector operators 17 will all remain in their extreme clockwise position resulting in the elongated portion 19, through the lugs 21, not exerting any pressure on any of the swingers 54, 58, or 62. As a result of such condition all of these swingers will remain in their unselected or right-hand positions in engagement with the contacts 56, 59, and 63, respectively. It is to be remembered that previously a "blank" combination was indicated as an idle channel designation for the multiplex apparatus and stated as occurring during the time that the transmitter 11 was not operating. However, because of the fact that the "blank" combination now occurs during the transmission of a message it is undesirable to allow such combination to be transmitted over the multiplex channel thereby indicating to the receiving equipment that an idle condition exists.

In order to remedy such condition it should be noted that the contact 56 associated with the uppermost or first swinger 54 is connected by means of a conductor 101 to the contact 56 associated with the second swinger, immediately thereunder. This swinger is connected by means of a conductor 102 to the third or middle swinger 54; this contact 56 is connected over conductor 103 to the fourth contact 56. The fourth swinger 54 associated with this contact is connected over conductor 104 to the contact 56 of the fifth or lowermost swinger 54 which is connected by means of conductor 105 to junction point 107.

At such time as the cam 24 on the shaft 22 presents its depression to the follower lever 69, which occurs after the feeler levers are moved to their upward tape sensing positions and which is before the contact pairs are set, the follower lever 69 will be pivoted in a clockwise direction under the urging of its spring to momentarily

close the contact pair 70. When such occurs, an electrical circuit is established which may be traced from positive battery 46, over a conductor 108, through the closed contact pair 70 to junction point 107, over the conductor 106, and through the circuit previously traced of the swingers 54 in their unselected positions and the conductors 104, 103, 102, and 101, through the uppermost swinger 54, over conductor 109, and through the winding of a relay 111 to ground. Upon the energization of the relay 111 its armature 112 will be attracted thereto which results in the establishing of a locking circuit for the relay which may be traced from ground through the winding of relay 111, through the armature 112 and the contact associated therewith with which it is then in engagement, over a conductor 113 to junction point 114, over a conductor 116 to junction point 117, over a conductor 118 to a contact 119, through the armature 121 which is normally in engagement with the contact 119, and over a conductor 122 to positive grounded battery 123. Thus, the relay 111 will remain in its energized condition until such time as the armature 121 is removed from engagement with the contact 119, as will be described hereinafter. Upon the energization of the relay 111 its armatures 124 to 128, inclusive, will also be attracted thereto. As may be seen, the upper contacts associated with the armatures 124 to 128, inclusive, are connected by the conductors 68 to the swingers 62 at the transmitter 11. The lower contact associated with the armatures 124 and 126 to 128, inclusive, are connected by means of a common conductor 131 to negative grounded marking battery 132. The lower contact associated with the armature 125 is connected over conductor 133 to an armature 134 which may move between an upper contact which is connected by conductor 136 to positive grounded spacing battery 137 and a lower contact connected over conductor 138 to a negative grounded marking battery 139. However, at this time the armature 134 will be in engagement with its upper contact.

At the same time as the above circuit was established upon the momentary closure of the contact pair 70, a second circuit is established which may be traced from grounded battery 46, over the conductor 108, through the closed contact pair 70 to junction point 107, over a conductor 141 and through the winding of a timing relay 142 to ground. Upon the energization of relay 142 its armature 143 will be attracted thereto which establishes a locking circuit for the relay which may be traced from ground, through the winding of the relay 142, through the attracted armature 143 to the associated contact, over a conductor 144 to junction point 146, over a conductor 147 to junction point 117, and thence over the previously described circuit comprising conductor 118, contact 119, armature 121, conductor 122 and grounded battery 123. The relay 142 will remain in an energized condition until locking battery is broken by the removing of armature 121 from contact 119, as will be hereinafter described. As a result of the energization of relay 142 its five associated armatures 148 will also be attracted thereto to remove them from engagement with their upper contacts which previously were connected over common conductor 149 to positive grounded spacing battery 151 and instead place them in engagement with associated lower contacts which are connected over conductors 152 to five armatures 153 to 157, inclusive. The armatures 153 to 157, inclusive, are movable be-

tween upper contacts which are connected by means of conductors 159 to the armatures 124 to 128, inclusive, respectively, previously described. The lower contact associated with the armatures 153 and 155 to 157, inclusive, are connected over 5 a common conductor 161 to negative grounded marking battery 162 whereas the lower contact associated with the armature 154 is connected to positive grounded spacing battery 163.

It should be noted that at the time relay 111 10 becomes energized its armature 86 will also be attracted thereto thus breaking the circuit which had previously been traced through the armature 86 and the lower contact 87 from the local segment 79 for the energization of the clutch magnet 26.

Remembering now that the relays 111 and 142 both are energized and held in that position, thereby attracting the armatures 124 to 128, inclusive, and the armatures 148 thereto, respectively, a line circuit is established which may be traced from negative marking battery 132 over the common conductor 131, through the armature 124 which is in engagement with its lower contact, over the conductor 159, through the armature 153 which is in engagement with its upper contact, over the conductor 152, through the first or upper armature 148 which is in engagement with its lower contact, to the No. 1 segment of the segmented distributor ring 71. At such time as the brush traverses the No. 1 segment, the circuit will be further traced through the brush, over the solid ring 73, and thence over the line conductor 74 to the multiplex channel. Such will result in the No. 1 impulse of the code combination being transmitted over the multiplex circuit as a marking condition.

It is to be remembered that the armature 125 was previously described as not being connected to common conductor 131 but instead as being connected over conductor 133. Thus, the next circuit which may be traced will be from positive spacing battery 131, over conductor 136, through the armature 134 now in engagement with its upper contact, over the conductor 133, through the armature 125 in engagement with its lower contact, over the conductor 159 to the armature 154, thence over the conductor 152 and through the second armature 148 now in its lower position, and over the conductor 72 to the No. 2 segment of the segmented distributor ring 71. At such time as the brush traverses the No. 2 segment a positive spacing impulse will be transmitted from the No. 2 segment over the brush, through the solid ring 73 and over the line conductor 74 to the multiplex channel, as the No. 2 impulse of the code combination.

If the circuits were to be traced which are established by the attraction of the armatures 126, 127, and 128 in engagement with their lower contacts, it would be seen that they would be traced similarly to that traced with respect to the armature 124. Therefore, as the brush traverses the Nos. 3, 4, and 5 segments, negative marking impulses will be transmitted over the line conductor 74 as the remaining three impulses of the code combination.

As a result of the circuits traced immediately above, we have seen that the code combination transmitted will consist of a negative marking impulse, a positive spacing impulse, and three negative marking impulses. Thus, instead of the transmission of a "blank" code combination, designated by five spacing impulses, which had been sensed in the tape, an entirely different code

combination has been transmitted over the multiplex channel which in the particular illustration consists of the code combination for the character "X."

After the brush has traversed the first five segments of the segmented ring 71 at some later time the brush associated with the local rings 76 and 78 will traverse the segment 79 associated with the particular apparatus which would normally cause the energization of the clutch magnet 26, resulting in the tape being stepped and a second combination being presented to the feeler levers. However, this will not occur because, as described above, the armature 86 was attracted upon the energization of the relay 111 thereby breaking the previously established circuit for the energization of the clutch magnet 26. Instead, an electrical circuit will be established which may be traced from the battery 77, through the solid ring 76 and the brush associated therewith, through the segment 79, over the conductor 81, through the armature 82 and the associated lower contact 83, over the conductor 84, through the armature 86, through the upper contact associated therewith, over the conductor 164 to junction point 166, through the armature 167 normally in engagement with its lower contact, over the conductor 168, and through the winding of a relay 169 to ground. As a result of the energization of the relay 169 a locking circuit is established from ground, through the winding of the relay 169, through the associated armature 171 attracted thereto, over the conductor 172, through the winding of relay 173 to junction point 114, thence over conductors 116 and 118, through contact 119 and armature 121, and over conductor 122 to grounded battery 123. The relay 173 which has been energized as a result of the locking circuit for the relay 169 causes its armatures 134 and 167 to be attracted thereto. As a result of the attraction of the armature 134 it will be moved from engagement with its upper to its lower contact thereby precluding positive spacing battery 137 from being connected with the armature 125 but instead connecting this armature with negative marking battery 139 by means of the conductor 138, the armature 134, and the conductor 133 to the armature 125. It might be noted that the relay 173 does not become energized until some time after the brush has completely traversed the segment 79.

As a result of negative marking battery 139 being impressed on the armature 125, at such time as the brush associated with the segmented ring 71 passes over the other three channel segments previously mentioned but not shown, and returns to traverse the first five segments connected over the conductors 72 to the relay bank 12, marking battery will be applied to the No. 2 segment. Inasmuch as the relays 111 and 142 are still in an energized condition through their locking circuits, as is relay 173, at the time that the brush traverses the No. 1 segment, an electrical circuit is established as previously described from negative marking battery 132, over the common conductor 131, through the armature 124, over the conductor 159 to the armature 153, over the conductor 152 to the uppermost armature 148, over associated conductor 72 to the No. 1 segment 70 of the segmented distributor ring 71, thence through the associated brush, through the solid ring 73 and over the line conductor 74 to the multiplex channel. Under this condition a marking impulse designating the No. 1 impulse of the code combination will be transmitted over the line. It

is to be remembered that under the prior description it was described that a spacing impulse was sent as the brush traversed the No. 2 segment. However, due to the energization of the relay 173 as the brush traverses the No. 2 segment an electrical circuit will be established from negative marking battery 139, over the conductor 132, through the armature 134 which is in engagement with its lower contact, over the conductor 133, through the armature 125 which is in engagement with its lower contact, over the conductor 159, through the armature 154, over the conductor 152 and through the second armature 148, through the conductor 72 to the No. 2 segment, through the brush to the solid distributor ring 73, and thence over the line conductor 74 to the multiplex channel. Thus, a marking impulse will now be transmitted as the No. 2 impulse of the code combination.

As the brush sequentially traverses the third, fourth and fifth segments of the segmented ring 71 electrical circuits will be established from the negative marking battery 132 to the armatures 126 to 128, inclusive, and over circuits similar to that described with respect to the armature 124 to the Nos. 3, 4, and 5 segments of the ring 71. As a result of such condition it may be seen that the entire code combination transmitted over the line conductor 74 to the multiplex channel will consist of negative marking impulses which under the standard code designates a "letters" combination. It is to be remembered that during the time that the "X" and "letters" combinations were transmitted as a result of the sensing of a "blank" code combination in the tape, the tape has not been stepped to its next code combination but has been held in the same position.

Inasmuch as the clutch release magnet 26 was not energized during the transmission of the "letters" combination the shaft 22 is not released for a cycle of rotation and, therefore, no electrical circuit is established for the energizing of the clutch release magnet 31 associated with the shaft 27. Therefore, during this period of time no code combination indicative of a "letters" combination will be transmitted over the start-stop circuit 29.

Sometime after the code combination of "letters" has been transmitted over the line conductor 74 to the multiplex channel, the distributor brushes will be advanced to a position whereat one of them will traverse the segment 79 of the local ring 78. At this time an electrical circuit will be established which may be traced from grounded battery 77, through the solid ring 76 and the associated brush to the segment 79, over the conductor 81, through the armature 82 to the associated lower contact 83, over the conductor 84, through the armature 86 and its upper contact with which it is now in engagement, over the conductor 164 to junction point 166, through the armature 167 which is now in engagement with its upper contact due to the locking battery applied to relay 173, over conductor 174 to junction point 176, and through the winding of a relay 177 to ground. As a result of the energization of the relay 177 its armature 121 will be attracted thereto, thereby removing it from engagement with its associated contact 119. Inasmuch as the locking circuits for the relays 142, 111, 173, and 169 had all been traced through the contact 119 and the armature 121 to battery 123, such circuits will now be broken and locking battery will be removed from all of these relays thereby resulting in their de-ener-

gization. As a result of such occurrence the armatures which had been attracted by the energization of the various relays will return to their original position and the apparatus will now be in a normal condition ready for the transmission of another character.

Simultaneously with the energization of the relay 177 over the circuit described above, a second electrical circuit is established which may be traced over the circuit just traced above to junction point 176, and thence over conductor 178 to junction point 89, over the conductor 91, through the winding of clutch release magnet 26, through the manual switch 92, over the conductor 93, through the swinger 94, through the associated contact 96 and to ground. As a result of the energization of clutch magnet 26 the shaft 22 will be released for rotation which, during the early part of its rotation, will cause the tape to be stepped and the contact operators 17 to be set in marking or spacing position in accordance with the code combination in the tape sensed by the feelers (not shown). Thus, the apparatus is once again ready to transmit a code combination at such time as the brush traverses the first five segments of the segmented ring 71 associated with this channel.

As was previously mentioned, the present apparatus provides means so that in the event that the character used to designate a "blank" condition in a message text on the multiplex channel is sensed in the same or another message text, a different designation will be transmitted over the multiplex channel so that the two may be distinguished from each other at the receiving station. Inasmuch as the character utilized to indicate a "blank" code combination was picked as the character "X" an assumption will now be made that the tape transmitter has sensed an "X" code designation which consists of a marking, spacing, and three marking impulses. As a result of such sensing the elongated members 19 will cause the first, third, fourth, and fifth swingers 58 to be positioned to their selected or left-hand positions in engagement with their associated contacts 61, whereas the second swinger 58 will remain in its unselected or right-hand position in engagement with its associated contact 59. At such time as the shaft 22 advances sufficiently to cause the cam 24 to operate the follower 69 and thereby close the contact pair 70 momentarily, an electrical circuit will be established which may be traced from grounded battery 46, over the conductor 108 and through the contact pair 70 to junction point 107, over the conductor 141 and through the winding of relay 142 to ground. Relay 142 will immediately become energized and will then be locked up through the armature 143 associated therewith to the battery 123 in a manner similar to that described previously for relay 142. As a result of such energization of relay 142 the armatures 148 will be attracted thereto and positioned in engagement with their lower contacts. A second circuit will also be established which may be traced from grounded battery 46, over conductor 108 and through the contact pair 70 to junction point 107, and thence to junction point 179, over the conductor 181, through the fifth swinger 58 and the left-hand contact associated therewith, over the conductor 182 and through the fourth swinger 58, through the left-hand contact 61 with which it is in engagement, over the conductor 183 and through the third swinger 58, through the left-hand contact 61 which it

engages, over the conductor 184 to the second swinger 58, through the right-hand contact 59 with which it is in engagement (No. 2 swinger not selected due to spacing condition), over a conductor 186 and through the first swinger 58, through the left-hand contact 61 with which it is in engagement, over conductor 187, and through the winding of relay 188 to ground. As a result of the energization of the relay 188 its associated armature 189 will be attracted thereto which will result in locking battery being applied to this relay from ground, through the winding thereof, through the armature 189, over a conductor 191 to junction point 146, over the conductor 147 to junction point 117, and thence over the conductor 118, through the contact 119, through the armature 121, and over the conductor 122 to grounded battery 123. The relay 188 will thus remain in an energized condition until such time as its locking circuit will be broken which will be described hereinafter.

Also as a result of the energization of the relay 188 its armatures 153 to 157, inclusive, will be attracted thereto placing them in engagement with their associated lower contacts. As a result of such movement of the armatures an electrical circuit may be traced from negative marking battery 162, over the common conductor 161 to the lower contact with which the armature 153 is in engagement, through the armature 153, over the conductor 152, through the first armature 148 which moved to its lower contact upon the energization of the relay 142, and over the conductor 72 to the No. 1 segment of the segmented distributor ring 71. Thus, at such time as the associated brush traverses the No. 1 segment a marking impulse will be transmitted over the line conductor 74 to the multiplex channel.

The second armature 154 was also moved to its lower position but instead of deriving battery over the circuit just described it will instead derive it from positive spacing battery 163 and the lower contact associated with the armature 154. This circuit may be further traced through the conductor 152, the second armature 148, and the conductor 72 to the No. 2 segment. Thus, as the brush traverses the No. 2 segment a spacing condition will be applied on the line conductor 74.

The armatures 155, 156, and 157 are connected to negative marking battery 162 in a manner similar to that as described with respect to armature 153 and thus, as the brush traverses the Nos. 3, 4, and 5 segments of the segmented ring 71 marking impulses will be applied to the line conductor 74. Thus, a code combination will be transmitted over the multiplex channel indicative of the character "X."

Inasmuch as the shaft 22 was released for rotation, as previously described, at an appropriate position in its cycle the cam 23 will cause the contact pair 44 to be closed thereby resulting in the energization of the clutch release magnet 31 which allows the shaft 27 to rotate and thereby transmit an "X" character designation over the start-stop circuit 29 in a manner which has previously been described.

After the transmittal of the "X" code combination over the multiplex channel as a result of the brushes traversing the first five segments of the segmented distributor ring 71, the brush associated with the solid ring 76 and the local ring 78 will at some later time traverse the local segment 79, thereby resulting in an electrical circuit being established from grounded battery 77, over the solid ring 76 and the bridging brushes,

through the segment 79 of the ring 78, over the conductor 81, through the armature 82 to its upper contact with which it is now in engagement, over a conductor 192 to junction point 166, through the armature 167, through the lower contact thereof and over the conductor 168 and through the winding of relay 169 to ground. As a result of the energization of the relay 169 its armature 171 will be attracted thereto which results in a locking circuit being established from the battery 123 and through the winding of the relay 173 in a manner which has previously been described. Due to the energization of the relay 188 and the subsequent attraction of its armature 82 no circuit may be established at this time to cause the energization of the clutch release magnet 26, thereby precluding rotation of the shaft 22 and operation of the transmitter 11 for a cycle of operation. Thereafter as the brushes traverse the first five segments of the segmented distributor ring 71 a second code combination indicative of the character "X" will be transmitted over the line conductor 74 to the multiplex channel over circuits which are identical to those traced immediately above for the transmission of the first character "X."

Inasmuch as the shaft 22 has been precluded from rotation for a cycle, or during the transmission of the second character "X," no similar code combination will be transmitted over the start-stop circuit 29 inasmuch as the stationary position of shaft 22 precludes closing of the contact pair 44 for the energization of the clutch release magnet 31.

After the brush traverses the first five segments to transmit the second "X" character designation, the other brush once again will traverse the segment 79 of the local ring 78 thereby bridging it with the solid ring 76 connected to battery 77 causing the establishment of an electrical circuit which may further be traced over the conductor 81 through the armature 82, through the upper contact with which it is now in engagement due to the energization of the relay 188, over the conductor 192 to the junction point 166, through the armature 167 and its upper contact in which it is now in engagement due to the energization of the relay 173, over the conductor 174 to junction point 176 and thence through the winding of the relay 177 to ground. The resultant energization of the relay 177 will cause its armature 121 to be attracted thereto thereby removing it from engagement with its associated contact 119 thus breaking the circuits from the battery 123 which had previously been traced as applying locking battery to the relays 142, 188, 173, and 169 thus resulting in all of these relays being de-energized. Upon de-energization of such relays the associated armatures will regain their position originally described whereby the apparatus is once again in condition to transmit another code combination over the multiplex channel.

Such other code combination will be available inasmuch as at the same time as the relay 177 was energized a second circuit was established which may be traced over the same circuit as just described up to junction point 176, and thence over conductors 178 and 91 and through the winding of clutch magnet 26 to ground, thereby causing the clutch magnet 26 to be energized. As a result of such energization the shaft 22 will once again be released for a cycle of rotation, thereby during its early part, causing the tape to be stepped to its next code combination position

and the contact operators 17 set in accordance with the marking or spacing conditions of the particular code combination to be sensed.

It is to be remembered that at the outset of the description an idle channel condition was discussed at which time the contact operators 17 were all in a clockwise or unselected position thereby allowing the swingers 62, through the elongated portion 19, to be in their right-hand position in engagement with contacts 63. Contacts 63, as was also described, were connected to the relay bank 12 by means of conductors 68. In tracing the circuit from the conductors 68 it is to be seen, with respect to the uppermost swinger 62 and associated conductor for example, that the circuit continues through armature 124, over conductor 159, through armature 153 and thence over conductor 152. However, because of the fact that the relay 142 is not energized at this time the associated armature 148 will be in its upward position in engagement with its upper contact thereby precluding continuation of the just traced circuit from the conductor 152 to the conductor 12 and thence to the No. 1 segment of the segmented distributor ring 71. However, a spacing or idle condition will still exist on the five segments indicating the present multiplex channel because of the fact that when the armatures 148 are in their upper position engaging their upper contact, an electrical circuit is completed which may be traced from positive grounded spacing battery 151, over the common conductor 149, through the armatures 148, over the conductors 12 to the five segments of the segmented distributor ring 71 comprising the present multiplex channel. Therefore, under this condition a spacing or idle channel condition will exist on the multiplex channel. Thus, even though the swingers 62 are positioned in an unselected or spacing condition the circuit is not traced therefrom for the multiplex channel.

The above idle condition exists only as long as the instant apparatus is not in operation with either the manual switch 92 open or the swinger 94 biased away from engagement with its associated contact 96 thereby preventing energization of the clutch release magnet 26.

It is, however, to be remembered that a condition has been described above wherein upon the receipt of a "blank" code signal appearing in a message text, the "blank" code combination is suppressed and instead "X," "letters" code combinations are transmitted over the multiplex channel. The difference between the two operating conditions is due to the fact that at such time as the instant apparatus is operating the manual switch 92 will be closed as will be the swinger 94, and contact 96, thereby allowing energization of the clutch release magnet 26 every time the brush traverses the segment 19. Immediately upon operation of the shaft 22 due to the energization of the clutch release magnet 26 the cam 24 thereon will cause the contact pair 70 to be closed resulting in the relay 142 being energized and locked up over circuits which have been previously traced. At such time as the relay 142 becomes energized the armatures 148 will be attracted thereto, thus removing them from engagement with their upper contacts and thereby removing positive spacing battery 151 from the armatures 148 and the conductors 12.

It is also to be remembered that previously in the description mention was made that if a code combination was sensed other than a "blank" or "X" combination, transmission of that code com-

bination would occur in accordance with the setting of the swingers 62. At that time mention was made that if the swinger 62 were in an unselected condition a circuit was completed to the positive spacing battery 66, whereas if it were in a selected or left-hand position a circuit was made with the negative marking battery 98. These circuits were traced through the swingers 62 to the conductors 68. Assuming now that a code combination exists which is neither "blank" nor "X" thereby not causing the reading relays 111 or 188 to be energized the circuit for the impulses of this code combination may be traced from the conductors 68 through the associated armatures 124 to 128, inclusive, which are in their upper position, over the conductors 159, through the armatures 152 to 157, inclusive, which are in their upper position, through the conductors 152, through the armatures 148, which are in their lower position due to the energization of the relay 142, and over the conductors 12 to the first five segments of the segmented ring 71. Thus, under this condition, as the brush bridges the solid ring 73 with the segmented ring 71, code impulses will be transmitted in accordance with the setting of the swingers 62 over the line conductor 74 to the multiplex channel.

It might be noted that when the code combination has been transmitted and the second brush traverses the segment 79 the circuit which was initially described for locking battery on the relay 142, through the armature 143, will be broken inasmuch as the relay 171 will be energized thereby attracting its armature 121 thereto removing it from engagement with its contact 119 and breaking the locking battery circuit. At the same time the clutch release magnet 26 will be again energized resulting in the shaft 22 being released for another cycle of rotation with a subsequent closure of the contact pair 70 for again causing the energization of the relay 142. The apparatus will now be ready to transmit the next code combination irrespective of what it may be when the brush once again traverses the first five segments of the segmented ring 71.

Thereafter, depending upon the particular code combination the apparatus will operate in a manner as has previously been described depending on whether a "blank," "X," or some other code combination is sensed and set in the associated contacts.

Therefore, it has been seen that in the event that a "blank" combination is sensed in a message text such combination will be suppressed and instead an "X" and "letters" combination will be transmitted over the multiplex channel. Likewise, in the event that an "X" combination is sensed and set in the associated contacts code combinations indicate of "X," "X" will be transmitted over the multiplex channel.

It should be noted that the relay 142 operates invariably; that is, becomes energized upon the setting of a character and thereafter becomes de-energized upon the transmission of that character, in a manner previously described. Thus, once a character has been transmitted it will not be transmitted a second time in the event that the contact operators 17 remain in the same position due to no new character being received and set up. However, in the event that a similar character is received and set up the relay 142 will operate to allow transmission of the same signal a second time, but only because a new signal has been received and the contact operators 17 have been repositioned, even though to the same positions.

This is true of the transmission of the last character by the pivoted transmitter, at which time the member 97 will cause the swinger 94 to open contact pair 96, thus precluding operation of the clutch magnet 26, and thereby preventing energization of the relay 142 which is dependent on the release of the shaft 22 and the closure of the contact pair 70. The operation of the member 97 is described fully in the above-identified Gubisch patent. Thus, this character will only be transmitted once even though the multiplex distributor 13 continues to rotate.

It is to be understood that the present example has been illustrative only and therefore designations other than the express ones described may be used.

As may be seen by reference to Fig. 1, the multiplex channel 74 will terminate at the receiving station in a receiving multiplex distributor 201 which has a solid and segmented ring similar to the rings 73 and 71, respectively, of Fig. 2. The particular multiplex channel associated with the instant receiving station will have five of the segmented distributor segments connected to a multiplex to start-stop converter 202 which may be of the type disclosed in U. S. patent application Serial No. 495,857, filed by W. J. Zenner on July 23, 1943, now Patent No. 2,382,596, issued Aug. 14, 1945. The start-stop signals will then be received by a perforator transmitter 203 which is of the type disclosed in the above-mentioned Gubisch patent. The signals incoming to the perforator transmitter 203 will cause a tape to be perforated in accordance with their code combinations in a perforator section 204 which is shown schematically in Fig. 1 only. The prepared tape will then be fed to a tape transmitter 206 which forms part of the perforator transmitter 203 and which is disclosed more in detail in Fig. 3. The perforator transmitter 203 is similar to the one shown in Fig. 4 and referred to in the description of Fig. 2. A distributor 207 also forms part of the perforator transmitter 203 and is also more fully disclosed in Fig. 3. A relay bank 208 is connected between the tape transmitter 206 and the distributor 207 in a manner and for a purpose to be described hereinafter.

By referring to Fig. 3 it may be seen that the tape transmitter 206 of the perforator transmitter 203 is very similar to that disclosed and described with respect to Fig. 2. A shaft 211 is provided which is under the control of a clutch release magnet 212 so that upon energization of the magnet the shaft will be released for operation. The clutch release magnet 212 is in an electrical circuit which may be traced from grounded battery 213, through the winding of the magnet 212, through a manually operable switch 214, through a contact pair 216 under the control of a member 217 which causes the contact pair to open at such time as the pivoted transmitter is in engagement with the punch block as described in the Gubisch patent, to ground.

The shaft 211 is provided with three cams 218, 219, and 221 which control individual cam followers 222 to 224, inclusive, respectively. Each of the cam followers is normally biased in a clockwise direction under the urging of individual springs. The cam follower 222 controls an associated contact pair 226 which is normally open, for a purpose to be described hereinafter. The follower 223 controls an electrical contact pair 227 which is normally closed whereas the follower 224 controls a contact pair 228 which is also normally closed.

The tape transmitter 206 is further provided with a plurality of slides 229 each of which controls a contact operator 231 similarly to that as described with respect to the transmitting station.

5 The contact operators 231 each have an elongated section 232 which has a plurality of lugs 233 thereon each of which controls an associated electrical swinger. As has previously been described, the slides 229 are set in accordance with the code 10 combination sensed in the tape and cause their associated contact operators 231 to be pivoted in a counterclockwise direction or not pivoted according to whether the particular impulse is of a marking or spacing variety.

15 The first lug 233 to the left of the contact operator 231 controls a swinger 234 which does not make electrical contact in its right or unselected position but which upon being selected or moved toward the left engages a contact 236. The 20 second lug 233 controls an electrical swinger 237 which may move between a left or right contact depending on whether the impulse is marking or spacing, respectively. The third lug 233 controls an electrical swinger 238 which may also 25 move between a left or right contact similarly as with respect to swinger 237. The final or fourth lug 233 similarly controls a swinger 239 which is also movable between a left and right contact depending on a marking or spacing condition. 30 While the above description has been made with respect to a single contact operator 231 and its associated swingers 234, 237, 238, and 239, it should be noted that each of the five contact operators 231 controls similar sets of swingers, 35 each set of which represents an impulse in the five impulse start-stop Baudot code.

Referring now to the distributor 207, also described as forming part of the perforator transmitter 203, it may be seen that it comprises a shaft 40 241 which is under the control of a clutch release magnet 242. The shaft 241 is provided with five cams 243 which have staggered low portions on the periphery thereof and operate to allow an associated follower 244 to pivot in a clockwise direction and close an associated contact pair 246 in a sequential manner with respect to the five cams. The shaft 241 is further provided with a sixth cam 247 which controls a follower 248 which in turn controls a contact pair 249. The cam 247 is so cut that during a stationary position of the shaft 241 the follower 248 will be free to pivot in a clockwise direction and close the associated contact pair 249.

A seventh cam 251 is also provided on the shaft 55 241 which controls an associated follower 252 which in turn controls an associated contact pair 253 which is normally in an open position. The distributor just described operates to transmit the start-stop code signals which have been received over the multiplex channel and converted to a local printer or over a start-stop circuit 263 to remotely located equipment.

In the operation of the present apparatus the slides 229 will be positioned in accordance with 65 the sensing of the tape after the shaft 211 has started into rotation. The contact operators 231 will operate in accordance with the positioning of the slides 229 to position their associated swingers 234, 237, 238, and 239 also in accordance with the 70 code combination sensed.

Just prior to the setting of the swingers but after the sensing pins have moved upwardly to sense the perforations in the tape, as is done in a well known manner, the shaft 211 will reach 75 such a position in its cycle of rotation whereat

the cam 211 will present its recess to the follower 222 thereby allowing the follower to pivot in a clockwise direction under the urging of its associated spring to close the contact pair 226. At this time an electrical circuit is established which may be traced from battery 256, over a common conductor 257, through the closed contact pair 226, over a conductor 258, and through the winding of the clutch release magnet 242 to ground. This will cause the magnet 242 to energize to release shaft 241 for operation.

Just prior to the release of the shaft 241, when the shaft is in a stationary position, the cam 247 thereon presents its recess to the follower 248 thereby allowing the follower to pivot in a clockwise direction to close the associated contact pair 249. Under this condition an electrical circuit is established from grounded battery 259, through the closed contact pair 249, over a conductor 261 to junction point 262, and thence over the start-stop circuit 263. Under this condition the start-stop circuit will be in its idle condition with marking on the line as is well known to those versed in the art.

Upon the initiation of rotation of the shaft 241 the cam 247 will be rotated with respect to the follower 248 causing the follower to be pivoted in a counterclockwise direction which results in the contact pair 249 being opened. Under this condition battery 259 cannot be applied to the start-stop circuit 263 but instead a zero or start condition will exist on the circuit, as is well known in start-stop telegraphy.

The contact pair 226 is closed only momentarily and therefore the clutch release magnet 242 is energized for a short period of time only. Therefore, the shaft 241 will only be released for one cycle of operation and will thereafter return to its stationary position until such time as the clutch release relay 242 is once again energized.

In the following operational description let us assume that the slides 229 and the associated contact operators 231 have been positioned in accordance with a perforated combination in the tape in some code combination which differs from either a "blank" or "X" combination, as described with respect to the transmitter station. As a result of such positioning of the swingers 234 as may occur, one or more of the swingers may be positioned in its selected or left-hand position in engagement with contact 236. If such occurs, an electrical circuit may be traced from grounded battery 264, over a common conductor 266, through the contact 236, through the selected swinger 234, and over a conductor 267 to the relay bank 208.

By reference to the relay bank 208 it may be seen that the just described circuit is continued from the conductor 267, through an armature 268 which is normally in its upper position in engagement with an associated contact, over a conductor 269, through the contact pair 246 at such time as it is sequentially closed, and over a common conductor 271 to the start-stop circuit 263. This will result in a marking impulse on the start-stop circuit 263 for each of the swingers 234 which has been selected and positioned in engagement with its associated contact 236.

In the event that a spacing condition exists with respect to swinger 234 it will remain in the position shown, not in engagement with any contact. Under this condition no electrical circuit is established and, therefore, when the contact pair 246 is closed in the sequential closing there-

of a zero or spacing condition will exist on the start-stop circuit 263.

Even though the swingers 237 to 239, inclusive, will also be positioned in accordance with the setting of the slides 229, it is sufficient to state at this time that their positioning to a right or left-hand contact will have no effect under this condition inasmuch as they control reading relays responsive only to a "letters" and "X" condition. The "letters" combination would have no effect on the reading relay under the control of the letters swingers 237 even though it were to be set up by the slides 229 at this time, for a reason which will become apparent hereinafter.

The tape transmitter apparatus 206 will operate continually upon the perforation of code combinations in the tape to cause these code combinations to be relayed to the start-stop circuit 263 similar to the manner just described.

It is to be remembered that with respect to the description of Fig. 2 it was pointed out that upon the occurrence of a "blank" combination, such combination was suppressed and instead "X" and "letters" combinations were transmitted over the multiplex channel 74. Also, upon the occurrence of an "X" condition it was converted to "X," "X" code combinations prior to transmission over the multiplex channel 74.

Let it now be assumed that a condition exists at the receiving station whereat the tape which is prepared by the perforator 204 reaches a position in the tape transmitter 206 where the swingers 229 will be positioned in accordance with "X," "letters" combinations designating a "blank" code signal transmitted. Under this assumed condition the slides 229 and associated contact operators 231 would be positioned in accordance with an "X" code combination which is represented by a marking impulse, a spacing impulse, and three marking impulses. Such a sensed code signal will cause the uppermost or No. 1 swingers and the Nos. 3, 4, and 5 swingers to be positioned in their selected position or toward the left in engagement with their associated left-hand contacts. The No. 2 swingers will remain in their unoperated position in engagement with their right-hand contacts. At such time as the swingers 238 and 239 are positioned in accordance with the description just given, an electrical circuit is established which may be traced from battery 256, over the common conductor 257, through the contact pair 227 which is normally closed, over a conductor 272, through the No. 1 swinger 238 which is positioned to the left, over a conductor 273 to the No. 2 swinger 238 which is positioned as shown or to the right, over a conductor 274 to the third swinger which is positioned toward the left, over a conductor 276 to the fourth swinger also positioned toward the left, through a conductor 277 to the fifth swinger also positioned toward the left, over a conductor 278 to junction point 279, over a conductor 281, through an armature 282 which is normally in its unattracted position in engagement with an associated upper contact, over a conductor 283 to the junction point 262 and to the start-stop circuit 263. The result of such circuit, which is established just prior to the opening of the contact pair 246 to establish a start condition on the start-stop circuit 263 is to operate as a shunt and thereby preclude a start condition from existing on the start-stop circuit 263. The result of such occurrence is that the start-stop circuit 263 remains as though there were an idle condition with marking on the line and the local printer or remotely lo-

cated equipment associated with the line will not respond in any manner to this "X" combination in the tape transmitter 206.

A second electrical circuit is established over the circuit previously traced to the junction point 279 and thence through an armature 284 which is normally in its unattracted position in engagement with its lower contact, over a conductor 286 to junction point 299, and through the winding of a relay 287 to ground. The relay 287 energizes and causes its armatures 288, 289, and 291 to be attracted thereto conditioning electrical circuits with their associated contacts but not establishing any at this time for reasons which will hereinafter appear. There is no locking circuit for the relay 287 inasmuch as it will remain energized over the circuit just traced for the period of time that the contact pair 227 is closed.

As was previously mentioned, the swingers 239 were also positioned similarly as were the swingers 238. Upon such occurrence a second electrical circuit may be conditioned from battery 256, through normally closed contact pair 228, over a conductor 292, through the swingers 239 and conductors connected thereto in a manner as was described with respect to the swingers 238, over a conductor 293 to junction point 294, thence over a conductor 296, through the winding of a relay 297, over a conductor 298, and through the armature 289 to junction point 299.

The relay 297 will not be energized, however, because as previously described positive battery was also applied over conductor 286 to junction point 299. Therefore, inasmuch as positive battery is applied to both sides of the winding of relay 297 no differential exists and, therefore, this relay cannot be energized. Thus, it has been seen that while the "X" of the "X," "letters" combination has been received it will not be retransmitted over the start-stop circuit 263. In other words, the instant apparatus under description acts to determine whether "X," "letters" or "X," "X" combination is being received for retransmission and controls the initial "X" to condition the apparatus only, no retransmission occurring thereof.

Near the end of the cycle of operation of the shaft 211 but while the contact pair 227 is still closed causing the relay 287 to remain energized, the cam 251 on the shaft 241 presents its recess to its follower 252 thereby allowing the follower to move in a clockwise direction under the urging of its associated spring thereby closing the contact pair 253. When this occurs a further electrical circuit is conditioned which may be traced from grounded battery 301, through the now closed contact pair 253, over a conductor 302, through an armature 303 which is in an unattracted position in engagement with its associated contact, over a conductor 304 to junction point 294, thence over conductor 296, through the winding of relay 297, over conductor 298, through the armature 289 to junction point 299. The relay 297 will not become energized at this time because as previously described positive battery was also applied over the conductor 286 to junction point 299 and therefore as positive battery is being applied to both sides of the winding of the relay 297 the relay will not energize. However, shortly after the contact pair 253 has been closed and while it is still in such condition the cam 219 will present its high portion to its associated follower 223 thereby pivoting the follower in a counterclockwise direction and allowing the contact pair 227 to open. As a result of the opening of this con-

tact pair a circuit no longer can be traced through the swingers 238 and eventually over the conductor 283 to the start-stop circuit 263 with the result that the marking on the line shunt circuit will no longer exist. However, such occurrence is so timed that the cam 247 will cause the contact pair 249 to be closed just prior thereto thereby supplying battery 259 to the start-stop circuit 263 and thus maintaining a marking condition on that circuit.

A second result of the contact pair 227 being opened is that positive battery is no longer applied over conductor 286 to the junction point 299 in opposition to the battery applied through the winding of the relay 297. Thus, at this time the relay 297 becomes energized due to the previous closing of the contact pair 253 over a circuit originating with battery 301 and which may be traced further from the junction point 299 and through the winding of relay 297 to ground. The relay 297 now becomes energized, attracting its armatures 282 and 284 thereto with the subsequent breaking of previously established electrical circuits.

Having assumed previously that the incoming signal was "X," "letters" combinations, the "letters" combination will now be set by the slides 229 in the various swingers associated with the contact operators 231. Inasmuch as a "letters" combination consists of all-marking code impulses all of the swingers will be positioned in their selected or toward the left position in engagement with their left-hand contacts. It is to be remembered that previously a circuit was described wherein upon the selection of one of the swingers 236 a circuit was established from battery 264, through the conductor 266, through the contact 236 and the swinger 234 and thence through the relay bank 208 to the distributor 207. However, such a combination is not desired at this time inasmuch as the original code combination was "blank" and not a "letters" combination. Therefore, at such time as the swingers 237 are moved in engagement with their left-hand contacts an electrical circuit is conditioned through the five swingers and their connecting conductors and over a conductor 306. Assume now that the shaft 211 has rotated sufficiently for its cam 219 to once again cause the contact pair 227 to be closed. An electrical circuit may be traced from battery 256, over the common conductor 257, through the contact pair 227, over the conductor 272, through the swingers 237 and their connecting conductors, over the conductor 306, through the armature 288 which is in its attracted position in engagement with its contact, over a conductor 307, and through the winding of a relay 308 to ground. The energization of the relay 308 will cause its armature 309 to be attracted thereto thus providing a locking circuit for the relay through the armature 309 and a conductor 311 back to the conductor 306, thus shunting the armature 309. Therefore, after the armature 288 no longer remains attracted the relay 308 will still remain energized. The energization of the relay 308 also causes its five armatures 268 to be attracted thereto removing them from engagement with their associated contacts. Thus, despite the fact that the swingers 234 have all been positioned in their selected position toward the left no circuit may be established from the battery 264, over conductors 267 to the contact pairs 246 for sequential closure because of the opening in the circuit at the armatures 268. Therefore, as the cams 243 sequentially close the associated con-

tacts 246, through the action of the followers 244, a spacing or zero condition will exist on the start-stop circuit 263 which will cause the apparatus associated therewith, either local or remote, to be operated in accordance with a "blank" code combination. Thus, it has been seen that upon the receipt of an "X," "letters" combination the apparatus at the receiving station will operate to convert these code combinations back to a "blank" code combination which they originally designated.

Even though the contacts 227 and 228 are held closed during the above-mentioned interval of the "letters" combination, they will have no effect with respect to the apparatus inasmuch as the second swingers 238 and 239 will both be positioned in their selected or left-hand position thereby precluding the tracing of an electrical circuit to either of the conductors 278 or 293.

After the contact pair 253 opens, battery will no longer be applied to the junction point 294 and, therefore, the relays 297 and 287 will become de-energized. However, inasmuch as this does not occur until after the relay 308 has become energized and locking battery is applied thereto, shunting armature 288, no adverse effect is had on the apparatus, particularly the relay 308.

The apparatus thereafter operates with the slides 229 setting a new character in accordance with the combination sensed in the tape. At such time the contact pair 227 will be open and no circuit may be traced through the swingers 237 and their conductors to apply locking battery to the relay 308, and therefore this relay will become de-energized which will allow its armatures 268 to return to their normal condition in engagement with their associated contacts. The apparatus will now be ready to repeat a cycle of operation.

Now assume that instead of "X," "letters" combinations being received by the instant apparatus "X," "X" code combinations are received which are indicative of the character "X" alone. The instant apparatus will operate with respect to the first "X" as has been described previously to cause the energization of the relay 287 and the shunt circuit for the start-stop circuit 263 during the receipt of the first "X." At such time as the second "X" is set in the swingers by means of the contact operators 231 the shunt circuit for the start-stop circuit 263 will no longer exist because of the energization of the relay 297 and the subsequent attracting of its armature 282, as previously described. Likewise, the circuit for the energization of the relay 287, through the conductor 286 and junction point 299 will no longer exist because of the attraction of the armature 284 to its upper contact instead of its lower contact. However, at this time the relay 287 will remain energized through a circuit including the swingers 239, the conductor 293 to the junction point 294, over the conductor 296, through the winding of the relay 297, over the conductor 298, through the armature 289, and thence through the winding of the relay 287 to ground. This circuit is established during the closure of the contact pair 228, prior to the time that the contact pair 253 is opened, therefore, insuring that the relay 287 will remain energized continually from the receipt of the initial "X" code combination.

An electrical circuit is established upon the setting of the swingers 238 in an "X" code combination which may be traced from the battery 256, through the common conductor 257, through

the now closed contact pair 227, over the conductor 272, through the swingers 238 and their associated contacts and connecting conductors (previously described), over the conductor 278 to junction point 279, through the armature 284 which is now attracted and in engagement with its upper contact, over a conductor 312, and through the upper winding of a relay 313 to ground. The relay 313 will become energized attracting its armature 314 thereto and thus supplying locking battery for the relay 313 through its lower winding, over a conductor 316, through the armature 291 which is in its attracted position in engagement with its contact, and through the contact to grounded battery 317.

As a result of the energization of the relay 313 and its remaining in a locked up condition the armature 303 will be attracted thereto removing it from engagement with its associated contact 20 and thereby precluding the electrical circuit through the contact pair 253 to the battery 301 in the event that such circuit were conditioned by the closure of the contact pair 253 through the action of the cam 251.

Inasmuch as an "X" code combination has been set up in the swingers 237, no electrical circuit may be traced through these swingers and their connecting conductors to cause the energization of the relay 308 because the second swinger 237 30 will be held in its unselected or right-hand position because of the second impulse of an "X" code combination being spacing, thereby precluding the completion of a circuit through the armatures and connecting conductors. Inasmuch as the relay 308 does not become energized the armatures 268 will remain in engagement with their associated contacts, thus completing circuits from the battery 264, through the contacts 236 and selected swingers 234. If the swinger 234 is in its unselected condition as the second one will be, no circuit will be established through the associated contact 236. Therefore, as the shaft 241 is released for rotation under the action of the clutch release magnet 242 and progresses sufficiently to cause the sequential closure of the contacts 246, code impulses indicative of an "X" combination; that is, marking, spacing, marking, marking, marking, will be transmitted over the start-stop circuit 263. Thus, a code signal indicative of the character "X" will be transmitted over the start-stop circuit 263, the initial "X" being completely suppressed during the operation of the apparatus.

After the code combination has been transmitted by the start-stop apparatus the contact pair 253 will be closed under the operation of the cam 251 and the follower 252, thereby conditioning a circuit for what has previously been described as holding the relay 287 energized during the interval of changing of the code combinations in the swingers under the control of the slides 229 and the contact operators 231. Inasmuch as the relay 313 is energized and the armature 303 is attracted thereto this circuit cannot be established and, therefore, at such time as the contact pair 228 is opened the relays 287 and 297 will become de-energized. At this time the armature 291 of the relay 287 will return to its unattracted position, breaking the circuit from battery 317 to the locking winding of the relay 313. The relay 313 will thus become de-energized allowing its armature 303 to assume its unattracted position in engagement with its contact in readiness for the possible establishment of a circuit from battery 301 through the contact pair 253 the next

time this contact pair is closed (next cycle of rotation of shaft 241).

Inasmuch as the relays 281, 291, and 313 have all become de-energized the apparatus is now in readiness to resume its operation upon the next incoming code signal. In the event that such signal were to be another combination the first character of which was "X," one of the two conditions previously described would occur and the apparatus would operate in a manner similar to that already described.

While the instant invention has been described with respect to particular apparatus, it is obvious that it could be incorporated in apparatus of other types where a similar need is present. Likewise, while specific code combinations have been utilized designating a "blank" code combination it is obvious that any desired code combination may be utilized. Thus, the specific disclosure is illustrative only and the invention may be embodied in other types of apparatus.

What is claimed is:

1. In a telegraph transmitter, means to initiate code combinations in accordance with perforations in a tape, means operating upon the initiation by said initiating means of a predetermined code combination to convert it to two code combinations neither of which are the same, and means operating upon the initiation by said initiating means of a code combination in the tape similar to the first of said converted code combinations to convert said code combination in the tape to two code combinations both of which are the same.

2. In combination with a telegraph transmitter, a multiplex channel, means to transmit all-spacing impulses over said multiplex channel when said transmitter is in an idle condition, means to initiate code combinations in accordance with the perforations in a tape when said transmitter is operating, and means operating when an all-spacing code combination is initiated during the operation of said initiating means to convert it to a different code combination for transmission over said multiplex channel.

3. In a telegraph receiver, means to receive code signals, a distributor under the control of said received code signals, means to shunt said distributor upon the receipt of a predetermined code signal, means to distinguish the code signal following said predetermined code signal, and means to convert said following code signal to a different code signal prior to the operation of said distributor if it designates a particular character.

4. In a telegraph receiver, means to receive code signals, a plurality of sets of contacts set in accordance with the received code signals, means under the control of one of said sets of contacts to cause said telegraph receiver to be nonresponsive to a predetermined code signal, and means under the control of another of said sets of contacts to cause another predetermined code signal to be converted to a still different code signal.

5. In a telegraph system including a transmitter and a receiver, code signal initiating means at said transmitter, means operating upon the initiation of a predetermined code signal to convert it to two code signals neither of which are the same, means operating upon the initiation by said code signal initiating means of a code signal similar to the first of said converted code signals to convert it to two code signals both of which are the same and are similar to the initiated code signal, means to transmit said code signals to said receiver, means at said receiver responsive to the received

code signals, means to suppress the first of the code signals of said converted two code signals, means conjointly responsive to said two different code signals to cause the second code signal to be converted, and means conjointly responsive to said two same code signals to allow the second code signal to be unaltered.

6. In combination with a transmitter having a pivoted tape sensing device for sensing the last character perforated, electrical contacts set in accordance with the sensing, and a member operated upon the sensing of the last character, a multiplex distributor, electrical contacts associated with said distributor, means operating after the sensing of a character for connecting said second-named electrical contacts with said distributor and said first-named electrical contacts, and means under the control of said member to preclude operation of said first-named means, whereby said second-named electrical contacts will not connect said distributor with said first-named electrical contacts after the transmission of the last character.

7. In combination with a transmitter having a pivoted tape sensing device for sensing the last character perforated, electrical contacts set in accordance with the sensing, and a member operated upon the sensing of the last character, a multiplex distributor, electrical contacts associated with said distributor, means operating after the sensing of a character for connecting said second-named electrical contacts with said distributor and said first-named electrical contacts, means associated with said distributor for releasing said first-named means from operation after the character has been transmitted by said distributor, and means under the control of said member to preclude operation of said first-named means, whereby said second-named electrical contacts will not connect said distributor with said first-named electrical contacts after the transmission of the last character.

8. In combination with a transmitter having a pivoted tape sensing device for sensing the last character perforated, electrical contacts set in accordance with the sensing, and a member operated upon the sensing of the last character, a multiplex distributor, electrical contacts associated with said distributor, a relay operating after the sensing of a character for connecting said second-named electrical contacts with said distributor and said first-named electrical contacts, and means under the control of said member to preclude operation of said relay, whereby said second-named electrical contacts will not connect said distributor with said first-named electrical contacts after the transmission of the last character.

9. In combination with a transmitter having a pivoted tape sensing device for sensing the last character perforated, electrical contacts set in accordance with the sensing, and a member operated upon the sensing of the last character, a multiplex distributor, electrical contacts associated with said distributor, means operating after the sensing of a character for connecting said second-named electrical contacts with said distributor and said first-named electrical contacts, means under the control of said member to preclude operation of said first-named means, whereby said second-named electrical contacts will not connect said distributor with said first-named electrical contacts after the transmission of the last character, and means to supply a blank signal combination to said second-named electri-

cal contacts and said distributor during the operation of said second-named means.

10. In combination with a transmitter having a pivoted tape sensing device for sensing the last character perforated, means set in accordance with the sensing, and a member operated upon the sensing of the last character, a multiplex distributor, means operating after the sensing of a character to operatively connect said means set in accordance with the sensing and said distributor to transmit signals, means under the control of said member to preclude operation of said last-named means, and means coacting with said means under the control of said member when it is operated to supply a blank signal combination to said distributor.

11. In combination with a transmitter having a pivoted tape sensing device for sensing the last character perforated, and a member operated upon the sensing of the last character, a multiplex distributor, means for supplying signals to said distributor for transmission from said sensing device after it senses a character, means under the control of said member operated upon the sensing of the last character to preclude said last-named means from supplying the last character sensed by said sensing device to said distributor more than once, and means under the control of said precluding means for supplying a blank signal combination to said distributor during the remainder of time that said member is operated.

12. In a telegraph transmitter, means to initi-

ate code combinations in accordance with perforations in a tape, means operating upon the initiation of a predetermined code combination by said initiating means to convert said code combination in the tape to a plural code combination each code combination of the plural code combination being different from said predetermined combination, said plural code combination always being the same upon every initiation of said predetermined code combination, and means operating upon the initiation of a predetermined one of said code combinations of said plural code combination by said initiating means to convert said code combination in the tape to a still different plural code combination, said still different plural code combination always being the same upon every initiation of said predetermined one of said code combinations of said first-mentioned plural code combination.
